UNITED STATES PATENT OFFICE.

GEORGE D. PUTNAM, OF ST. LOUIS, MISSOURI.

DIE.

1,109,783.

Specification of Letters Patent.

Patented Sept. 8, 1914.

Application filed April 18, 1914. Serial No. 832,703.

To all whom it may concern:

Be it known that I, GEORGE D. PUTNAM, a citizen of the United States, residing in the city of St. Louis and State of Missouri, have invented a new and useful Die, of which the following is a specification.

This invention relates to dies used for forming the blanks for boots and shoes, and other articles for which dies embodying the principles of the present invention may be used.

The object of the invention is to provide a die comprising a continuous integral wall which is thicker above and thinner in its middle portion and which is so constructed that it presents outwardly an upper and a lower peripheral flange with an intervening, depressed, unbroken peripheral surface joined by inclines with the surfaces of the flanges so that said flanges and said intervening depression form a handhold tending to crowd together, and away from both edges, the fingers of the operator, thus preventing the fingers from becoming extended across the edges of the die.

The function and superior utility of the construction are apparent when it is considered that such construction constitutes an efficient safeguard to prevent injury to the hands of the user; that such construction enables the user more firmly to grasp and manipulate the die; and that such construction considerably reduces the weight and quantity of material in the die, and also reduces the cost and expense of manufacture of the die.

In the accompanying drawing in which I have illustrated a die embodying the principles of my invention—Figure 1 is a perspective view illustrating a die of the type used by shoe manufacturers, constructed in accordance with my invention. Fig. 2 is a cross sectional view of the die illustrating the extended upper and lower portions by which all of the fingers of the hand grasping the die will be pressed together against the intermediate unobstructed outer surface of the web.

The die is in the form of a continuous integral wall and includes a lower body portion 1 having a vertical inner surface 2 and a oblique outer surface 3, and terminating in a cutting edge 4. The upper portion 5 of the die is integrally connected with the lower portion by a relatively thin web 6 so

that the lower portion 1 and the upper portion 5 present outwardly upper and lower peripheral flanges between which is the intervening, depressed, unbroken peripheral surface of the web 6. The inner walls of the upper and lower and intermediate parts of the die are in the same vertical plane, so that pressure applied to the upper portion 5 of the die will be transmitted directly to the cutting edge 4.

The web 6 is essentially of considerable width, so that all, or a number, of the fingers of the hands may be grasped upon the web 6 between the upper portion 5 and the lower portion 1 of the die. At the union of the web 6 and the lower portion 1 a sloping or inclined wall 7 is formed so that the lower fingers of the hands grasping the die will be pressed away from the cutting edge of the die. Similarly, a sloping or inclined wall 8 is formed at the union of the web 6 with the upper portion 5 of the die.

When the die is manually engaged all of the fingers of the hands grasping the die will be pressed together onto the web 6 and away from the edges of the die, thus efficiently guarding and protecting the hands and preventing the fingers from slipping over the edges of the die and becoming mangled. The entire outer surface of the web 6 presents an intervening, depressed, unbroken peripheral surface which is joined with the flanges 1 and 5 by the inclined walls 7 and 8 so that said peripheral surface is essentially devoid of any projections or elevations which would tend to spread or slip any of the fingers toward either of the edges of the die should the fingers not be accurately and precisely placed when they are engaged on the die. The construction of my improved die thus eliminates all danger of the fingers slipping toward the edges of the die and becoming mutilated or mangled due to any carelessness or oversight of the user in grasping the die. Also, all of the fingers are pressed together away from the edges of the die, thus dispensing with the high degree of care necessary to avoid accidents with the use of dies of different construction.

What I claim and desire to secure by Letters Patent is—

A cutting die, comprising a continuous integral wall, thicker above and thinner in its middle and presenting outwardly an up-

per and a lower peripheral flange and an intervening depressed unbroken peripheral surface joined by inclines with the surfaces of the flanges; said flanges and intervening depression forming a handhold tending to crowd together, and away from both edges, the fingers of the operator.

In witness whereof, I have signed this specification in the presence of two subscribing witnesses.

GEORGE D. PUTNAM.
